SIGNAL DEVICE AND SYSTEM

Howard J. Findley, Cleveland, Ohio, assignor to
The Bishop & Babcock Mfg. Company, Cleve-
land, Ohio, a corporation of Ohio

Application September 14, 1933, Serial No. 689,412

12 Claims. (Cl. 177—7)

This invention relates to signal systems and apparatus and particularly to electrical systems and apparatus adapted to be installed upon a vehicle such for example as an automotive vehicle 5 whereby the driver thereof may effect an audible signal to the driver of another vehicle or to other persons generally.

It is an object of the invention to provide an improved signal system and apparatus of the 10 class referred to.

Another object is to provide an improved signaling system and apparatus of the class referred to whereby audible signals of a distinctive character may be made.

Another object is to provide an improved system and apparatus whereby audible signals may be made having the character of a musical tone or tones.

Another object is to provide an improved signal system and apparatus whereby audible signals may be made having the character of a plurality of harmonious musical tones.

Another object is to provide a musical tone producing signal system and apparatus whereof the 25 musical tones may be selectively changed and/or adjustably varied.

Another object is to provide an audible signal system and apparatus whereby a musical tone or tones may be produced in an improved manner.

Another object is to provide an improved signaling system and apparatus for producing a plurality of musical tone signals and having means for sounding the tones at will in any selective sequence whereby to produce audible signals 35 having the character of tunes.

Another object is to provide, for electric signal systems and apparatus of the class or classes referred to hereinabove, an improved electric control circuit or circuits.

Another object is to provide, in an improved signaling system and apparatus for producing a plurality of musical tone signals at will, and selectively, an improved controller means for selecting the tones to be produced.

Other objects will be apparent to those skilled in the art to which my invention appertains.

My invention is fully disclosed in the following description taken in connection with the accompanying drawings, in which:

Fig. 1 is an elevational view partly in cross-section of a sound-producing device which I may employ in the practice of my invention;

Fig. 2 is a diagrammatic view of one form of 55 an electric circuit which I may employ in con-

nexion with the device of Fig. 1 for electrically energizing the same;

Fig. 3 is a cross-sectional view partly in elevation of a rotary contacting device which I may employ and which is illustrated to a smaller scale 5 diagrammatically in Fig. 2;

Fig. 4 is an elevational view taken from the plane 4—4 of Fig. 3;

Fig. 5 is a fragmentary sectional view taken 10 from the plane 5—5 of Fig. 4;

Fig. 6 is a diagrammatic view illustrating another electric circuit or system which I may employ in connection with the device of Fig. 1;

Fig. 7 is a side sectional view to an enlarged scale of a controller means illustrated diagrammatically in Fig. 6; 15

Fig. 8 is a fragmentary sectional view taken from the plane 8—8 of Fig. 7;

Fig. 9 is a sectional view of a device or means 20 for introducing a time element in the operation of my invention which may be used instead of a thermal device as illustrated in Fig. 2 or 6;

Fig. 10 is a fragmentary plan view taken from the plane 10—10 of Fig. 2;

Referring to Fig. 1, I have illustrated at 1, 25 generally, a sound amplifying horn and at 2, generally, an electrically energizable sound-producing device responsive, upon the reception thereby of electric current impulses, to translate the same into sound waves for amplification by 30 the sound amplifying horn 1.

The horn 1 and device 2 may be variously constructed. In the illustrative example thereof of Fig. 1, I have shown at 3 and 4 housing elements having peripheral flanges 5 and 6 clamped together by bolts 7 and clamping therebetween a transversely vibratory diaphragm 8. Suitable annular rings 9—9 may be interposed between the diaphragm and the flanges. 35

Secured to a central portion of the diaphragm 40 is a tubular winding support 10 having wound thereon an armature winding 11. The winding 11 extends inwardly axially between inwardly radially extending poles 12—12 of an E-form electro-magnetic circuit 13, the central pole 14 of which extends axially into the tubular support 10 and therefore into the winding 11. A field winding 15 is provided on the central pole 14 and thus when energized generates magnetism in the gap between the poles 12 and the central pole 14. 45

In a manner well known in the art, impulses of current directed into the winding 11 will cause it to move axially and vibrate the diaphragm 8 by reaction of the current in the winding 11 upon the 50 magnetic field in which it is disposed as above 55

described. The sound thereby produced by the diaphragm 8 is amplified by the horn 1, the air column in the horn communicating with the air in contact with the diaphragm 8, in a chamber 16 5 provided between the diaphragm and the housing portion 3.

Circuit wires 17 and 18 and circuit wires 19 and 20 are, respectively, led into the housings 3-4 to energize the field winding 15 and the armature winding 11 respectively in a manner to be described.

Referring to Fig. 2, I have indicated diagrammatically the diaphragm 8, the field magnet 13, armature winding 11, field winding 15, the field circuit wires 17 and 18 and the armature winding circuit wires 19 and 20.

A source of current such as a storage battery 21 is provided, connected at one terminal to the wire 18 and at the other terminal by a wire 22 to ground.

It is one of the advantages of my invention that it is particularly applicable to motor vehicles, and in such applications, the storage battery of the vehicle may be advantageously employed as the battery 21.

At 23 is indicated a switch of the push button type having a terminal connected by a wire 24 to ground and another terminal connected to a wire 25.

At 26 is illustrated a thermostat, such for example as a bimetallic thermostat rigidly supported at one end 27 and at the other end free to move with changes of temperature. Associated with its free end is a resilient switch arm 28 normally resiliently engaged with a stationary switch contact 29 when the thermostat is in the low temperature condition. A second switch arm 30 is mounted to move with the thermostat when heated to engage a stationary contact 31. An adjusting screw 32 threaded into the free end portion of the thermostat and engaging by its head the arm 30, is provided to adjust the gap at the contact 31 so that it will be engaged at the instant that the contact 29 is disengaged by the resilient arm 28, the arm 28 remaining in engagement with the contact 29 through a part of the movement of the thermostat due to the resilience of the arm 28.

A heating element 33 is provided for the thermostat, one terminal of which is connected to the wire 25 and the other of which is connected to the wire 17.

As will now be apparent, upon closing the push button switch 23, current may flow from the battery 21 by wire 18 through the field winding 15 and then by wire 17 through the heating element 33 to the wire 25, and thence through the switch to ground. The thermostat will accordingly, after the elapse of a time interval during which it is being heated, move to break the contact at 28-29 and make contact at 30-31 for a purpose to be described.

When the switch 23 is closed, current also flows from the battery 21 by wires 18 and 20 through the armature winding 11 and by wire 19, thermostat 26, contacts 28-29, and wire 34, to and through a vibratory contact device 35 and thence by wire 36 to the wire 25 and through the push button switch 23, energizing the armature winding 11, the energization being pulsating or intermittent due to the vibratory device 35 which will now be described.

This device 35 comprises an electromagnet having a preferably laminated E-form core 37, a

winding 39, an armature 38 in the form of a vibratory reed fixed at both ends as by screws 40 and 40' to arms of a frame 41 and carrying at its middle portion a contact 42 engageable with a stationary contact 43 on an adjusting screw 44 supported in a stationary support 45 on the frame 41 insulated therefrom, as at 46. The circuit through the device is by way of a wire 34 above described, the winding 39, to a ground on the frame and thence to the reed 38, contacts 42-43 10 and to the wire 36 electrically connected to the screw 43 through the support 45.

When the current flows as above described, energization of the magnets 39-37 attracts vibrator reed armature 38 and breaks the circuit at 43-42 15 whereupon the vibratory reed retracts and again closes the circuit at the contacts 43-42. Thus the reed will vibrate back and forth interrupting the current in the circuit of the armature winding 11. The reed 38 may have a normal 20 periodicity of vibration and this may be adjustably changed through a limited range by a flat metal adjusting element 47 clamped under the screw 40, overlapping the adjacent end portion of the reed 38; and the amount of overlap being 25 adjustably variable by means of an elongated slot 47' in the element 47.

The device 35 will thus operate automatically to interrupt the current in the circuit of the armature winding 11 and by choosing a reed 38 30 of vibrating frequency of a musical tone, the armature winding 11 will be energized with impulses of musical tone frequency and, as will now be clear, will cause a musical tone to be limited by the sound amplifying horn 1. And as will also be apparent, this tone will continue, if the switch 23 is held closed, until the heater 33 has heated the thermostat 26 to the point where it will move upwardly as viewed in the drawings to break the circuit of the armature winding 11 at the contacts 28-29 whereupon it will cease.

My invention contemplates producing this single musical tone in this manner as a signal for short intervals of time, or for the sounding of short duration signals, the switch 23 on such 45 occasions being only momentarily closed. Where, however, a signal of longer duration is desired, it may be effected by means which will now be described by merely holding the switch 23 closed for a longer period.

At 50 is illustrated a small electric motor having circuit wires 51 and 52 connected respectively to the wire 18 and the wire 25 whereby upon closing the switch 23, the motor will be energized and will start to turn. The motor has an extension 55 shaft 53 supported in bearings 54-54 and between the bearings carries a plurality, such as four, current interrupting devices 55-55 illustrated diagrammatically in Fig. 2 and illustrated in one actual embodiment in Figs. 3, 4 and 5. The mode of operation will first be described in connection with Fig. 2 and thereafter the actual device by which it may be effected will be completely described.

When the thermostat 26 has moved upwardly 65 as viewed in the drawings and closes the contacts 30-31 and assuming that the switch 23 is maintained closed, to operate the motor 50, current may flow from the battery 21 through the wire 18, armature winding 11, wire 19, thermostat 26, 70 contacts 30-31, and by a wire 56 and wires 57-57 to the several current interrupting rotary devices 55 and through the same to the shaft 53 whence it may flow through a current collecting brush device 58 and a wire 59 to the wire 52 75

and thence by the wire 28 to the switch 23, to complete the circuit.

The rotation of the current interrupting devices 55 by the motor 58 causes each of the devices 55 to break up the current into impulses. With respect to the rotational velocity of the motor 58 and the number of interruptions of each device 55 per revolution, each device causes impulses to occur at the frequency of a musical tone. The periodicity of the impulses of the several devices 55 are chosen corresponding to the several tones or notes of a musical chord and thus the impulses energizing the armature winding 11 will be current impulses composed of a plurality, such as four, impulses of different frequencies; that is to say, the current impulses will be composite impulses and the tone emitted by the horn, caused by the energization of the armature winding 11 by such impulses, will be a tone of beautiful quality and harmonious effect.

My invention contemplates the employment of a single device 55, and in such case it will now be clear that the tone emitted by the horn will be a more or less simple or single musical tone of any desired pitch determined by the periodicity of the interruption effected by the device 55; and as just stated, where a plurality of devices 55 is employed, each of different periodicity, the horn will emit a composite or chord type of tone.

As will now be clear, therefore, when the push button or other switch 23 is closed and held closed, the thermostat 26 will be in its lower position as viewed in the drawings and the device 55 will cause the horn to emit a musical tone of a predetermined pitch, preferably a relatively low pitch. While this is going on, the motor 58 will be started and come up to speed and then, after a predetermined short interval, determined by the heating effect of the heating element 33, and thermal responsiveness of the thermostat 26, the thermostat will move upwardly as viewed in the drawings, cutting off the emission of the single musical tone and initiating the single or preferably composite tone through the agency of the devices 55. Thus, for short signals, the single relatively low tone may be produced and for longer signals this may be produced followed after a short interval by the composite chord tone. Thus a very beautiful and effective result is obtained.

One form of construction for the current interrupting devices 55 will now be described in connection with Figs. 3, 4 and 5.

The extension 53 of the motor shaft is preferably separate from the main shaft 63 of the motor and is coupled thereto by an insulating coupling 61. The shaft extension 53 is rotatably supported in bearings 54—54 formed in the legs 63 and 64 of a U-shaped frame 62 preferably molded from insulating material. Between the legs 63 and 64 is a rotor 65 mounted on the shaft extension 53 and formed from metal and with a plurality of contacting points 66—66 extending axially from each side thereof, and with insulating compound 67 molded on the rotor between the contact points, the entire rotor being in the form of a disc, and the contact points 66 and the insulation 67 providing opposite planar faces on the rotor.

The contact points 66 are arranged in a plurality of circular groups as plainly shown in Fig. 4 and are preferably elongated radially. In Fig. 4 is illustrated the right-hand face of the disc as viewed in Fig. 3 and there is provided four circular series of contact points, which circular

series may be indicated by reference characters C, E, G and B. The opposite face of the rotor 65 is not separately illustrated but will appear similar to the right-hand side which is illustrated in Fig. 4, and also may be provided with four circular series of contact points.

The leg 63 of the frame is provided with four perforations extending axially therethrough, in which perforations are disposed corresponding plungers 68, 69, 70 and 71. Through the other leg 64 extends a similar set of four plungers 72, 73, 74 and 75. The perforations and the plungers are preferably rectangular as indicated in Figs. 4 and 5 and the bores through which they extend may be disposed radially as shown in Fig. 4. Upon the leg 63 are mounted four flat spring elements 76 resiliently pressing upon the outer ends of the plunger 68—71 to resiliently hold them inwardly in their bores and to hold their inner ends resiliently upon the corresponding face of the rotor 65. On the other leg 64 of the frame is a corresponding set of flat springs for holding the plungers 72—75 inclusive against the opposite face of the rotor. The springs 76 are secured upon the legs by screws 77 projected therethrough, and the screws 77 also clamp into position on the frame electric terminal connections 78—79.

Extending radially through the lower part or closed end of the U-shaped frame is a brush 80 engaging at its inner end the periphery of the rotor 65 and at its outer end spring-pressed by a spring 80 secured to the frame 62 by a screw 81 and provided with a thermal connector 82.

Circuit wires 57 may be connected to the terminals 78 and a circuit wire 59 to the terminal 82.

When the motor 58, which may be connected to the shaft 60, rotatably drives the rotor 65 by the shaft extension 53, the contact points 66 rapidly and successively engage the plungers 68 to 71 and whenever a contact point engages a plunger, an electric circuit is completed from one of the wires 57, through the corresponding spring 76 and the said plunger, and a contact point 66 to the rotor 65, and thence by brush 80 and spring 80 to the wire 59; and this circuit will be rapidly made and broken, or interrupted, by the rapid engagement and disengagement of the said plunger with the contact points of one of the circles of contacts on the rotor.

Where the system of Fig. 2 is employed, where it is desired to effect the interruption of the circuit comprising the wires 56 and 58 by four interrupting means of different frequencies, only one face of the rotor 65, such as that illustrated in Fig. 4, is employed. Each of the devices 55 of Fig. 2 corresponds to one of the circles of contacts C, E, G and B of Fig. 4. The device of Figs. 3 and 4 may be connected in the system of Fig. 2 as indicated by the reference characters common to Fig. 2 and to Figs. 3 and 4; and as will now be clear, the motor 58 will drive the rotor 65 and the circuit 56—58 will be interrupted periodically in a manner to effect the production of four sets of impulses of different frequencies.

By providing a suitable number of contact points 66 in each of the circles of contacts on the rotor 65, the interruptions of the circuit by each circle may be caused to occur at the frequency which will produce four musical tones of a musical chord as described for the devices 55 of Fig. 2.

In Fig. 9 I have shown a modification for introducing the time interval hereinbefore referred to, and which may be used instead of the thermo-

stat device of Fig. 2. In this modification, a shaft 90 is driven by the motor 50 and has thereon a sliding sleeve 91. Centrifugal weights 92—92 are connected to flat spring devices 93—93, one end of each of which is connected as at 94 to the shaft and the opposite end to the sleeve 91.

On the sleeve is a metal ring 95 of relatively great axial extent and a short ring 96, connected to the ring 95 and insulated therefrom

10 by an intermediate insulation ring 100.

The wire 19 (see Fig. 2), is connected to a brush 97 bearing on the ring 95; and the wire 34 is connected to a brush 98 bearing on the ring 96; and the wire 56 is connected to a brush 99 bearing upon a portion of the sleeve 91 preferably made from insulating material.

When the shaft 90 is started into rotation by the motor 50, the circuit from the wire 19 is completed to the wire 34 from the brush 97, through the ring 95, through the ring 96 and out at the brush 98. After the motor comes up to speed, the weights 92 will have moved outwardly radially and cause the springs 93 to draw the sleeve 91 toward the left as viewed in Fig. 9, and then the circuit from the wire 19 will be established to the wire 56 from the ring 95 to the ring 96 and out by way of the brush 99, the circuit to the brush 98 being broken upon the insulating portion 100 of the ring.

30 Thus with this arrangement also, the circuit to the single tone device will first be made and then after an interval of time has elapsed during which the motor will speed up, the circuit to the multi-tone producing elements will be, as above described, established and the former circuit broken.

In the form of my invention shown in Figs. 6, 7 and 8, means is provided to produce any one of a plurality of musical tones by the horn 1 selectively, or any number of them from one 40 to eight of different pitch and in unison, or to sound them individually or in combination in any desired succession or sequence to play tunes thereby.

At 105 is illustrated a controller means comprising a switch 106 preferably of the push button type and a plurality of switches, preferably of push button type, 107—107, the latter preferably being disposed in a circular arc with the switch 106 at the center thereof, and all supported upon a suitable housing 108 illustrated separately in Fig. 7. The radial distance from the switch 106 to the switches 107 is preferably that suitable for engagement of the push button switch 106 by the palm or heel of the operator's hand and the concurrent engagement of the push button switches 107 by the fingers of the operator's hand.

Upon closing the switch 106, current may flow from the battery 200 by wires 109 and 110 to a motor 111, and thence by wires 112 and 213 to the switch 106 and thence by wire 113 to ground, completing the circuit. At the same time current may flow by wire 109 and a wire 114 to the field winding 15 of the sound producing device, and thence by wires 115 and a wire 116 to the wire 213, and so on to ground through the switch 106.

The motor 111 then starts and comes up to its full speed. By the closing of the switch 106 another circuit also is closed from the wire 109 through a wire 117 and the heating element 118 of a thermostat 119 and thence by wire 120 and wire 115 to the switch 106 and to ground.

The circuit of the armature winding 11 is by way of wire 109 and a wire 121 to the armature winding, and thence by a wire 122 to a stationary

contact 123 of a thermostatic switch of which the element 119 is the thermostatic element. A movable contact 124 is carried on the thermostatic element 119 for engagement to the contact 123; and the said circuit is adapted to be completed, from the contact 124 through the thermostat 119 and by a wire 125 to a sliding contact 58 on an extension shaft 53 of the motor 111.

Upon the shaft extension is a plurality, such as eight, of devices 55 through which current may flow from the brush 58 and shaft 53 over one or more wires 126—126 to the push button switches 107, and thence by wires 127—127 to the wire 113 and thence to ground.

After energizing the heating element 118 as above mentioned, and after the elapse of a pre-determined interval of time, the thermostatic element 119 will respond to the increase of temperature and close the contacts 123—124. This 20 interval of time is sufficient to allow the motor 111 to come up to full speed, and after the said contacts 123—124 have been closed, if any one or more of the push button switches 107 are closed, current may flow over the circuit above described 25 including the devices 55 to energize the armature winding 11. The current flowing over the circuit will be interrupted by each of the devices 55 and it will energize the armature 11 with a pulsating current in each case of a musical tone 30 frequency.

The frequency of interruption by the devices 55 may be the frequencies of an octave of the diatonic musical scale, and thus by suitably and successively closing the push button switches 107 a 35 tune may be played on the horn device 1; or, a number of the switches 107 may be closed simultaneously to cause the horn to emit the sound of a musical chord. If a single button 107 be pressed, a single interrupting device 55 will be in 40 circuit and a single musical tone will be produced. Where more than one of the devices 55 are placed in the circuit by the switches 107, the pulsating current to the armature winding 11 will be a composite pulsating current composed of a 45 plurality of pulsating currents.

Thus a great variety of signal effects and/or musical effects may be produced by the horn device 1 accordingly as the push button switches 107 are closed singly, in chord combinations, or in 50 musical tune sequence.

Any suitable construction for the controller means 105 may be provided. One form is shown in Figs. 7 and 8. The button 106 may have a stem 128 sliding axially in a bore in a wall of the housing 108. A spring of the leaf type 129 may normally hold the button 106 outwardly and may be bent downwardly by pressing on the button and caused to engage a contact element 130 to close a circuit between the wires 113 and 213. The 60 push button switches 107 may have stem portions 131 sliding in suitable bores in the housing wall and may normally be held outwardly by spring contact elements 132; and when the buttons are depressed, the arm 132 may be depressed into contact with a spring contact element 133 to close a circuit from the wire 126 to the wire 113.

The stem 131 of the push button 107 may have a laterally extending pin 134 normally movable in a groove 135 in a boss 136 on the housing; and the button may be depressed and then rotated to bring the pin 134 under the boss as shown in dotted lines at 137 to retain the button in the depressed position and to retain the contact elements 132 and 133 closed. Thus as an alterna- 75

tive mode of operation, any one or any suitable number of the buttons 107 may be retained in closed position and then at any time upon closing the button switch 106, the armature winding 11 will be energized with the pulsating current (after closure of the contacts 123-124 at the end of the predetermined time interval), and thus the sounding of the musical tone may be placed under the control of the button 106 alone, and upon closing this switch the horn will emit a single tone or a chord of tones as preselected.

If desired, the control means 105 may in every case be operated first by depressing the button switch 106 and then the switches 107, in which case an auxiliary horn 139 may be provided under the control of an auxiliary push button 140 on the steering wheel of the vehicle which when closed will energize the horn over a circuit including a wire 141 connecting one contact of the button to the ground, a wire 142 connecting the other contact of the button to the horn, and a wire 143 connecting the horn to the wire 109, and thence through the battery 108 to ground.

The current interrupting devices 55 of Fig. 6 may be variously constructed. One form is that of Figs. 3, 4 and 5, herein. This device has been described in connection with Fig. 2 where four different frequencies of current impulses were employed. Where an octave of musical tone frequencies is desired, both sides of the rotor 65 may be utilized. The left side of the rotor as viewed in Fig. 3 may be provided with four circular sets of contact points such as the points 66-66 to successively engage the plungers 72, 73, 74 and 75.

The contact points 66 on the right-hand side of the rotor 65 as viewed in the drawings may pass under their respective plungers 68 to 71 inclusive to make contact at the plungers at a frequency corresponding to four musical tones of the diatonic scale, such for example as the tones C, E, G and B; and the contact points on the other side of the rotor may effect contact with their plungers at frequencies corresponding to the other tones of the same scale, namely D, F, A and C. The frequency of the impulses in each case will, as will be understood, be determined by the number of contact points 66 in the circular series in each case.

In connecting the device of Figs. 3 and 4 into the circuit of Fig. 6, it will be understood that the wire 59 of the device corresponds to the wire 126 of the diagram, and the wires 57 of the device correspond to the wires 126 of the diagram. As will now be clear, current impulses of any musical tone frequency in an octave of the diatonic scale may be taken from the plungers 68 to 75 respectively and singly or in any preselected group by closing the circuit thereto by the buttons 107; and that such pulsating currents will energize the armature winding 11 with a single or composite pulsating current, as the case may be, to correspondingly energize the sound-producing device 3.

My invention is not limited to the exact details of construction shown and described. Many changes and modifications may be made within the scope and spirit of my invention without sacrificing its advantages. Whereas in the foregoing specification and in the appended claims I have referred to the apparatus as producing musical tone frequency and to the sound-producing device as emitting musical tones, it is not to be inferred that my invention is limited to the production of signal tones having the aesthetic quality usually associated with the word "musical"; and such expressions as "musical tone" in

the appended claims are to be taken as meaning any defined tone of definite frequency which can be audibly produced as a signal.

I claim:

1. In a signal system and apparatus, in combination, a sound-producing device responsive to produce sound when energized by undulatory electric current, an energizing circuit and current source therefor, a first electrically actuatable means for producing in the circuit, impulses of a predetermined musical tone frequency to cause the sound-producing device to produce a corresponding first musical tone, a second electrically actuatable means for producing in the circuit current impulses of musical tone frequency to cause the sound-producing device to produce a second corresponding musical tone, operable means to control both electrically actuatable means, and operable for periods of varying time duration at the will of the operator, and for repeated operations of less than a predetermined maximum duration, repeatedly effecting production of the first musical tone, and automatic means to effect production of the second musical tone after optional production of the first musical tone at the will of the operator beyond said maximum duration.

2. In a signal system and apparatus, in combination, a sound-producing device responsive to produce sound when energized by undulatory electric current, an energizing circuit and current source therefor, a first electrically actuatable means for producing in the circuit, impulses of a predetermined musical tone frequency to cause the sound-producing device to produce a corresponding first musical tone, a second electrically actuatable means for producing in the circuit current impulses of musical tone frequency to cause the sound-producing device to produce a second corresponding musical tone, operable means to control both electrically actuatable means, and operable for periods of varying time duration at the will of the operator, and, for repeated operations of less than a predetermined maximum duration, repeatedly effecting production of the first musical tone, and automatic means to effect production of the second musical tone and cessation of the first musical tone after optional production of the first musical tone at the will of the operator beyond said maximum duration.

3. In a signal system and apparatus, in combination, a sound-producing device responsive to produce sound when energized by undulatory electric current, an energizing circuit and current source therefor, a first electrically actuatable means for producing in the circuit, impulses of a predetermined musical tone frequency to cause the sound-producing device to produce a first corresponding musical tone, a second electrically actuatable means for producing in the circuit current impulses of musical tone frequency composed of a plurality of different frequencies to cause the sound-producing device to produce a second corresponding musical tone composed of a plurality of harmonious tones, operable means to control both electrically actuatable means, and operable for periods of varying time duration at the will of the operator, and, for repeated operations of less than a predetermined maximum duration, repeatedly effecting production of the first musical tone, and automatic means to effect production of the second musical tone after optional production of the first musical tone at the will of the operator beyond said predetermined maximum duration.

4. In a signal system and apparatus, in combination, a sound-producing device responsive to produce sound when energized by undulatory electric current, an energizing circuit and current source therefor, a first electrically actuatable means for producing in the circuit, impulses of a predetermined musical tone frequency to cause the sound-producing device to produce a first corresponding musical tone, a second electrically actuatable means for producing in the circuit current impulses of musical tone frequency composed of a plurality of different frequencies to cause the sound-producing device to produce a second corresponding musical tone composed of a plurality of harmonious tones, operable means to control both electrically actuatable means, and operable for periods of varying time duration at the will of the operator, and, for repeated operations of less than a predetermined maximum duration, repeatedly effecting production of the first musical tone, and automatic means to effect production of the second musical tone after optional production of the first musical tone at the will of the operator beyond said predetermined maximum duration.
5. In a signal system and apparatus, in combination, a sound-producing device responsive to produce sound when energized by undulatory electric current, an energizing circuit and current source therefor, a first electrically actuatable means for producing in the circuit, impulses of a predetermined musical tone frequency to cause the sound-producing device to produce a first corresponding musical tone, a second electrically actuatable means for producing in the circuit current impulses of musical tone frequency composed of a plurality of different frequencies to cause the sound-producing device to produce a second corresponding musical tone composed of a plurality of harmonious tones, operable means to control both electrically, actuatable means, and operable for periods of varying time duration at the will of the operator, and, for repeated operations of less than a predetermined maximum duration, repeatedly effecting production of the first musical tone, and means to effect production of the second musical tone and cessation of the first musical tone after optional production of the first musical tone at the will of the operator beyond said predetermined maximum duration.
6. In a signal system and apparatus, in combination, a sound-producing device responsive to produce sound when energized with undulatory electric current, an energizing circuit and current source therefor, a motor driven current commutator for producing in the circuit impulses of musical tone frequency to cause the sound-producing device to emit musical tones; the current interrupter comprising a rotor and stator, one provided with a plurality of sequentially disposed contacts and the other provided with a contact successively engageable thereby at musical tone frequency upon relative rotation of the rotor and stator, an energizing circuit for the motor, operable means for effecting energization of the motor circuit, and automatic means to effect energization of the sound producing device at the end of a predetermined time interval after energization of the motor.
7. In a signal system and apparatus, in combination, a sound-producing device responsive to produce sound when energized with undulatory electric current, an energizing circuit and current source therefor, a motor driven current com-

mutator for producing in the circuit impulses of musical tone frequency to cause the sound-producing device to emit musical tones; the current interrupter comprising a rotor and stator, one provided with a plurality of sequentially disposed contacts and the other provided with a contact successively engageable thereby at musical tone frequency upon relative rotation of the rotor and stator, a thermal time element device, energizing circuits for the motor and thermal device, operable means for effecting energization of the motor circuit and of the thermal device, and the thermal device effecting energization of the sound-producing device at the end of a predetermined time interval after energization of the motor.

8. In a signal system and apparatus, in combination, a sound-producing device responsive to produce sound when energized with undulatory electric current, an energizing circuit and current source therefor, a first electrically actuatable means for producing in the circuit impulses of a predetermined musical tone frequency to cause the sound-producing device to produce a first corresponding musical tone, a motor-driven actuatable means for producing in the circuit current impulses of musical tone frequency composed of a plurality of different frequencies to cause the sound-producing device to produce a second corresponding musical tone composed of a plurality of harmonious tones, an energizing circuit for the motor, a time element device, an electric energizing circuit therefor, a single operable means to effect energization of the motor circuit and time element device and first electrically actuatable means, and the time element device effecting energization of the sound-producing device by the motor-driven means after a predetermined time interval following energization of the motor circuit and energization of the sound-producing device by the first electrically actuatable means.

9. In a signal system and apparatus, in combination, a sound-producing device responsive to produce sound when energized with undulatory electric current, an energizing circuit and current source therefor, a first electrically actuatable means for producing in the circuit impulses of a predetermined musical tone frequency to cause the sound-producing device to produce a first corresponding musical tone, a motor-driven actuatable means for producing in the circuit current impulses of musical tone frequency composed of a plurality of different frequencies to cause the sound-producing device to produce a second corresponding musical tone composed of a plurality of harmonious tones, an energizing circuit for the motor, a thermal time element device, an electric energizing circuit therefor, a single operable means to effect energization of the motor circuit and thermal time element device and first electrically actuatable means, and the thermal time element device effecting energization of the sound-producing device by the motor-driven means after a predetermined time interval following energization of the motor circuit and energization of the sound-producing device by the first electrically actuatable means.

10. In a signal system and apparatus, in combination, a sound producing device responsive to produce sounds when energized with undulatory electric current, an energizing circuit and current source therefor, a motor-driven current commutator for producing in the circuit impulses of musical tone frequency to cause the sound producing device to emit musical tones, an energiz-

ing circuit for the motor, operable means for effecting energization of the motor circuit, and automatic means to effect energization of the sound producing device at the end of a predetermined time interval after energization of the motor.

11. In a signal system and apparatus, in combination, a sound producing device responsive to produce sounds when energized with undulatory electric current, an energizing circuit and current source therefor, a motor-driven current commutator for producing in the circuit impulses of musical tone frequency to cause the sound producing device to emit musical tones, a thermal time element device, energizing circuits for the motor and thermal device, operable means for effecting energization of the motor circuit and of the thermal device, and the thermal device effecting energization of the sound producing device

at the end of a predetermined time interval after energization of the motor.

12. In a signal system and apparatus, in combination, a sound producing device responsive to produce sounds when energized with undulatory electric current, an energizing circuit and current source therefor, a motor-driven current commutator for producing in the circuit impulses of musical tone frequency to cause the sound producing device to emit musical tones, a delayed operation device, energizing circuits for the motor and delayed operation device, operable means for effecting energization of the motor circuit and of the delayed operation device, and the delayed operation device effecting energization of the sound producing device at the end of a predetermined time interval after energization of the motor.

HOWARD J. FINDLEY.
